SAFETY RAZOR

Alex Pascoo, New York, N. Y.

Application October 11, 1944, Serial No. 558,128

2 Claims.

(Cl. 30—55)

1

This invention relates to improvements in safety razors.

One of the important features of the invention resides in quick and simple means of releasably securing the clamping member and guard member together with a conventional razor blade interposed therebetween.

Another feature of the invention is to provide a safety razor having a reversible handle by which the razor may either be used in a manner wherein the handle extends from beneath the head, or from one end of the head for use in the manner of a "straight" razor.

Other features of the invention will become apparent as the following specification is read in conjunction with the accompanying drawing in which,

Figure 1 is a perspective view of a safety razor constructed in accordance with my invention.

Figure 2 is a perspective view of the safety razor shown in Figure 1 but with the parts in separated relation.

Figure 3 is an enlarged horizontal sectional view on the line 3—3 of Figure 1.

Figure 4 is a vertical transverse sectional view on the line 4—4 of Figure 3.

Referring to the drawing by reference characters and at present to Figures 1 to 4 thereof, the numeral 10 designates a safety razor constructed in accordance with my invention. The razor 10 includes a guard member 11, and a clamping member or cap 12 between which a double edge blade 13 is securely clamped in flexed position by a novel separable connecting means presently to be described. The members 11 and 12 are preferably made of metal but they may be made of plastic material if desired.

The guard member 11 comprises a rectangular shaped body 14 having rearwardly offset guard edges 15—15. Elongated slots 16—16 parallel the guard edges 15—15. The body 14 is provided with a centrally located elongated slot 17 and with a pair of blade positioning lugs 18—18 respectively disposed beyond the ends of the slot 17. Integral with one end of the body 14 of the guard member is a straight hollow handle 19, the front side of which is flush with and parallel to the front face of the body 14, so that the thickness of the handle extends rearwardly beyond the plane of the rear face of said body. The handle 19 is shown as being square in cross section and open at its inner end. Slidable within the open end of the handle 19 is a latch element 20, the same being square in cross section while the outer end is bifurcated as at 21, the furca-

tions of which are respectively disposed beyond the plane of the opposite longitudinal edges of the slot 17. The furcations are connected by a latching tongue 22 of a length less than the bifurcation. The rear wall of the handle is provided with an elongated slot 23 through which a manipulating element 24 extends, said element being fixedly secured to the slidable latch element 20. Sliding movement of the latch element 20 is limited in opposite directions by engagement of the manipulating element 24 with opposite ends of the slot 23.

The blade clamping member or cap 12 has a lug 25 extending centrally from the inner side thereof which is of a thickness and width to freely pass through the slot 17. Extending inwardly from one side edge of the lug 25 is a keeper notch 26, the same being of a width to tightly receive the tongue 22. If desired, the wall 27 of the notch 26 may be slightly inclined to enable the tongue to wedgely engage the same for reasons to be hereafter appreciated. The inner side of the clamping member 12 is provided with recesses 28—28 which are complementary to the positioning lugs 18—18 to receive the same when the members 11 and 12 are clamped together with the blade 13 interposed therebetween.

The blade 13 is a conventional double edge blade having positioning lug receiving slots 29 therein.

In practice, assume that the parts of the razor 10 are in separated condition as shown in Figure 2. To assemble the parts for use of the razor, the blade 13 is placed flat against the front side of the guard member body 14 with the positioning lugs 18—18 passing through the slots 29. The inner side of the clamping member 12 is now applied against the seated blade 13 and the lug 25 thereof is freely inserted through the slot 29 in the blade and through the slot 17 in the guard body 14. The latching element which is shown in Figure 2 as being in retracted position is now slid outwardly by pressing the finger against the manipulating element 24, whereupon the furcations of the bifurcation 21 are slid into embracing engagement with opposite flat sides of the lug 25 while the tongue 22 tightly enters the keeper notch 26. This latching action causes the members 11 and 12 to be drawn into tight clamping relation sufficient to flex the blade 13 and hold the same in rigid position for shaving purposes. When using the razor for shaving the same is held and manipulated in the manner of a conventional straight razor. The clamping member 12, guard member 11 and blade 13 may be sepa-

rated for cleaning purposes by pushing upon the manipulating element 24 to slide the latch element to retracted position, whereupon the tongue 22 will become disengaged from the keeper slot 26 of the lug 25.

While I have shown and described what I consider to be the preferred embodiment of my invention, I wish it to be understood that such changes in construction, design, and materials as come within the scope of the appended claims 10 may be resorted to without departing from the spirit of my invention.

Having thus described the invention, what I claim as new and desire to secure by Letters Patent is:

1. In a safety razor, a guard member having an elongated slot therein centrally thereof, a clamping member, a flat lug integral with the clamping member centrally thereof and freely passing through the elongated slot, said lug having a keeper slot extending inwardly from one side edge thereof, a tubular handle fixed to one end of the guard member and extending therefrom in parallel relation thereto, and a latch element 25 slidably mounted in said handle and releasably seated in said keeper slot for clamping

4
securing the guard member and clamping member together.

5 2. In a safety razor, a guard member having an elongated slot therein centrally thereof, a clamping member, a flat lug integral with the clamping member centrally thereof and freely passing through the elongated slot, said lug having a keeper slot extending inwardly from one side edge thereof, a tubular handle integral with one end 10 of the guard member and extending outwardly therefrom in parallel relation thereto, a latch element slidably mounted in the inner end of said tubular handle and having a bifurcated portion extending therefrom to receive said lug, a locking tongue connected to and bridging the space between the furcations of the bifurcated portion of the latch element for seating in said keeper slot to 15 clampingly secure the clamping member to the guard member, said tubular handle having a slot 20 therein, and a manipulating element fixed to said latch element and extending through the last named slot whereby said latch element may be slid back and forth to latching and unlatching positions.

ALEX PASCOO.
